UNITED STATES PATENT OFFICE

95,004

DESIGN FOR A TOY BOAT

Joseph Kennard Weddell, New York, N. Y.

Application November 20, 1934, Serial No. 54,088

Term of patent 14 years

To all whom it may concern:

Be it known that I, Joseph Kennard Weddell, a citizen of the United States, residing at New York city, county of New York, and State of New York, have invented a new, original, and ornamental Design for Toy Boats, of which the following description, in connection with the accompanying drawing, is a specification.

The figure is a side elevation of a toy boat, illustrating my design.

The design is characterized particularly by a

line indicating the water line and distinctly separating the above and below water portions of the hull, which portions are preferably contrastingly colored.

The opposite side of the article is the same in configuration as the side shown in the drawing.

I claim:

The ornamental design for a toy boat as shown and described.

J. KENNARD WEDDELL.
